CABLE WINDING DRUM OR SHEAVE

Filed Sept. 2, 1930

INVENTOR:—
GEORGE A. ALLEN.
By Martin P. Smith ATTY.

UNITED STATES PATENT OFFICE

1,927,673

CABLE WINDING DRUM OR SHEAVE

George A. Allen, Montebello, Calif.

Application September 2, 1930. Serial No. 479,178

3 Claims. (Cl. 242—117)

My invention relates generally to cable winding drums or sheaves and more particularly to a renewable and reversible shell for drums or sheaves and the principal object of my invention is to provide a relatively simple and practical construction embodying a shell or sleeve that is removably positioned upon the body of a sheave or drum, thereby enabling the outer or wear receiving portion of the sheave or drum to be easily and quickly renewed in the event of breakage or excessive wear, or said shell or sleeve may be conveniently reversed in position upon the body of the drum or sheave in order to equalize the wear that said sleeve or shell receives from the cable that operates thereon.

A further object of my invention is, to provide a cable winding drum or sheave having a renewable wear receiving shell that is relatively simple in construction, inexpensive of manufacture, capable of being easily and quickly applied to or removed from the body of the drum or sheave and which improved construction effects a material saving in the cost of repairs and renewal of parts that become worn to such a degree as to be unfit for service.

With the foregoing and other objects in view, my invention consists in certain novel features of construction and arrangement of parts that will hereinafter be more fully described and claimed and illustrated in the accompanying drawing in which:

Fig. 1 is a side elevational view of a drum or sheave constructed in accordance with my invention.

Fig. 2 is an elevational view looking in the direction indicated by the arrow 2 in Fig. 1.

Fig. 3 is a longitudinal section taken on the line 3—3 of Fig. 1.

Fig. 4 is an end elevational view looking in the direction indicated by the arrow 4 in Fig. 1.

Referring by numerals to the accompanying drawing which illustrates a practical embodiment of my invention, 10 designates the cylindrical body of a cable winding drum or sheave, which body is secured in any suitable manner upon a power driven shaft 11. Formed integral with the inner end of this cylindrical body 10 is an outwardly projecting circumferential flange 12 and the opposite end portion of the body is externally threaded as designated by 13.

Formed in the outer portion of flange 12 is a notch or a plurality of notches 14.

The removable shell or sleeve that forms a part of my improved drum, comprises a hollow cylindrical member 15, the opening through

which receives the body 10 and formed integral with the ends of the shell or sleeve 15 are outwardly projecting circumferential flanges 16.

The flange 16 at the inner end of the shell fits directly over flange 12 at the inner end of the body 10 and formed integral with the outer portion of this flange 16 is a lug 17 or a series of lugs that are adapted to occupy the corresponding notches 14 when the sleeve is properly positioned upon the body of the drum.

The outer one of the flanges 16 has formed integral therewith, a lug or lugs 18 that are practically identical with the lugs 17 and these lugs are adapted to occupy notches 19 that are formed in a washer 20 that is positioned on the outer portion of the drum body 10 and which bears directly against the outer face of the outer one of the flanges 16.

When shell 15 is properly positioned upon the body 10 and the washer 20 is properly positioned on the outer portion of said body against the outer one of the flanges 16, the threaded outer portion of body 10 projects a short distance beyond the washer 20 and receives a nut 21, the inner end of which bears against the outer face of washer 20, thereby securely retaining the parts in assembled relation.

As a result of my improved construction the body of the drum or sheave 10 is provided with a readily removable shell or sleeve that is interlocked with said body by means of the lugs 17 and 18 that engage respectively in the notches 14 and 19 and in the event that the shell becomes worn as a result of the operation of the cable thereupon, or if said shell becomes cracked and broken as a result of rapid changes in temperature produced by the friction of the cable that operates on the surface of said drum, said shell or sleeve may be readily removed and replaced.

Inasmuch as the shell portion of the drum is capable of being removed, it is not necessary to discard the entire drum in the event that the shell or sleeve becomes worn or broken as a result of wear developed by the winding and unwinding of the cable on the shell or sleeve.

In some instances or where only a limited number of turns of cable are carried on the drum, one end portion thereof, or that portion upon which the cable bears will wear much more quickly than the other portion and where such uneven wear occurs, the shell or sleeve may be readily removed and reversed in position upon the body of the drum, thereby providing a practically unworn cable receiving surface.

Thus it will be seen that I have provided a cable winding drum or sheave winding drum or sheave that is relatively simple in construction, inexpensive of manufacture and very effective in performing the functions for which it is intended.

It will be understood that minor changes in the size, form and construction of the various parts of my improved cable winding drum or sheave may be made and substituted for those herein shown and described without departing from the spirit of my invention, the scope of which is set forth in the appended claims.

I claim as my invention:

- 15 1. A cable winding drum or sheave comprising a cylindrical body, a shell removably arranged on said body, interengaging means between said shell and body and means including a nut and washer for securing said shell upon said body.
- 20 2. In a cable winding drum or sheave, a substantially cylindrical body, a flange integral with one end thereof, a collar removably mounted

on the other end of said cylindrical body, a shell removably positioned on said body and provided with flanged end portions that overlie the flange on the body and said collar, the end of the cylindrical body opposite the flanged end being threaded, a nut seated on said threaded end and a washer arranged between said nut and the adjacent end of the shell, which nut is interengaged with the end of said shell.

3. In a cable winding drum or sheave, a substantially cylindrical body, a flange integral with one end thereof, a collar removably mounted on the other end of said cylindrical body, a shell removably positioned on said body and provided with flanged end portions that overlie the flange on the body and said collar, interengaging means between the flanged ends of said shell, the flange on the body and said collar and a nut screw-seated on the end of the cylindrical body opposite the flanged end thereof for retaining the collar and shell on said cylindrical body.

GEORGE A. ALLEN.
